(57) **CLAIM**

The ornamental design for a stool collection tool, as shown and described.

DESCRIPTION

FIG. 1 is a perspective view of a stool collection tool, showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a line cross section view, along 8-8 in FIG. 2, thereof; and,

FIG. 9 is a reference view showing the state in which the stool collection stick is housed in the container thereof.

The broken lines depicting the stool collection container represent environmental structure and form no part of the claimed design, while the broken lines depicting the stool collection stick illustrate portions of the stool collection tool that form no part of the claimed design.
